UNITED STATES PATENT OFFICE.

STEFAN WIMMER, OF WEST NEW YORK, NEW JERSEY.

PORTABLE ELECTRIC-LIGHT STAND.

Application filed September 26, 1924. Serial No. 740,065.

To all whom it may concern:

Be it known that I, STEFAN WIMMER, a citizen of the Republic of Austria, residing at West New York, in the county of Hudson and State of New Jersey, have invented certain new and useful Improvements in Portable Electric-Light Stands; and I do hereby declare the following to be a full, clear, and exact description of the invention, such 10 as will enable others skilled in the art to which it appertains to make and use the same.

This invention relates to improvements in portable electric light stands and has for its 15 object to provide a stand so constructed that, in addition to its regular base, the stand shall be provided with means permitting the stand to be secured to various objects, such as the arm of a chair or other 20 objects where it may be desirable to secure the same.

The various features of novelty and invention will appear from the detailed description taken in connection with the accompanying two sheets of drawings forming 25 part of these specifications.

Referring to the drawings:

Fig. 1 is an elevation of the improved lamp stand, parts of the base being broken 30 away to illustrate certain features of construction.

Fig. 2 is a vertical section taken on line 2—2 of Fig. 1.

Fig. 3 is an enlarged sectional view of the 35 mechanism at the top of the lamp stand.

Fig. 4 is a sectional view taken at right angles to that shown in Fig. 3.

Fig. 5 is a view showing how the lamp stand may be secured to a flat object, the 40 base members of the stand being utilized in conjunction with clamping means within the pedestal.

Fig. 6 is a horizontal section through the lamp stand.

Fig. 7 is a view showing how the stand 45 may be secured to a round object by clamping means contained within the pedestal of the same.

Fig. 8 is a fragmentary detailed view of a 50 modified form of structure, namely, the flexible clamping member and associated fulcruming means.

In the drawings number 1 indicates the 55 electric lamp, 2 the socket within which the said lamp is received, and 3 the wires carrying current to the lamp. The pedestal form-

ing part of the lamp stand is generally indicated by numeral 4 and at the bottom of the same is fixedly secured a collar 5 having an annular bottom flange 6, the top of the 60 collar being threaded to receive a ring nut 7. Surrounding the collar between the flange 6 and nut 7 is a ring 8 having a laterally extending bracket 9 in the nature of spaced lugs between which the lamp socket 2 is turnably supported as by means of a pin 10. The lamp supporting ring 8 is turnably mounted on the collar 5 so as to permit the lamp to be swung around the pedestal. 65

Turnably mounted on the lamp supporting ring 8 is a member 11 provided with outwardly extending ears or lugs 12 and 13, these lugs forming supports for base members 14 and 15. As shown in Fig. 6 these base members are of sufficient area to support the pedestal in a stable upright position when the said members are arranged as in Fig. 1. Each base member is provided with a lug 16 for connection between their respective pairs of lugs 12 and 13. 70

Each of the base members 14 and 15 is provided with a stop lug 17 adapted to bear against the annular flange 6 on the collar 5 and with a stop lug 18 adapted to bear against the ring member 11 to which said base members are connected, as clearly shown in Fig. 1. These stop lugs on the base members prevent said members from turning about their hinges, as will be readily understood. 75

Means are provided to permit said base members 14 and 15 to be turned downwardly with respect to the pedestal, for a purpose hereinafter mentioned. To permit this turning of the base members the flange 6 is provided with diametrically opposed re-entrant or cut-out portions 19 into which the bottom stop lugs 18 may be received when the ring 11 to which they are hinged is given a quarter revolution from the position shown in Fig. 1. The base members may then be swung about their hinges in a position as shown in Fig. 5, said members then functioning like jaws for clamping an object, such as a table top T between them with the aid of mechanism presently to be described. Each base member 14 adjacent its rim is provided with a pocket-like member generally indicated by numeral 20, and constituted by a plate 21 suitably secured to the base members. 80

Adjustably mounted on the pedestal 4 is

a sleeve 22 having pivoted thereto at opposite sides, as at 23, levers 24, the lower end of each of which has an angular extension 25 adapted to enter any one of a series of 5 openings 26 in the pedestal 4, it being understood that the sleeve is provided with an opening through which said extensions may project, as clearly indicated in Fig. 3. When the upper extremities 27 of said 10 levers are pressed toward each other, the angular extensions 25 of the same will be removed from the openings 26 in the pedestal, thus permitting the sleeve to be bodily shifted on the pedestal. Means are provided for normally retaining said extensions 25 in said openings 26, said means constituting springs 27' arranged within the cylindrical housing members 28 on opposite sides of the sleeve 22, said spring pressing 15 against plungers 29 located in the ends of said housing members, said plungers bearing against the terminal ends 27 of said lever 24.

The lever carrying sleeve 22 is surrounded by an internally threaded nut 30, the nut being suitably confined by means of annular flanges or rings 31 and 32 attached to the sleeve in any suitable manner.

At this point it may be stated that the 30 pedestal 4 is conveniently made in the form of a rectangular tube and consequently the sleeve 22 has a rectangular opening. Also the terminals 27 of the levers 24 are made 35 wide enough so that the pair of springs 28 may be employed for spreading them apart, the springs being located on opposite sides of the sleeve.

The pedestal 4 is provided with a longitudinal slot 33 in each of a pair of opposed 40 side walls. Arranged within the pedestal is a transversely extending plate 34 having trunnion-like extensions extending through the side slots 33 and secured to the sides of the sleeve 22, as indicated at 35 in Fig. 4. When the sleeve 22 is shifted along the 45 pedestal 4, said plate 34 is moved therewith.

Also arranged within the pedestal and extending transversely therein is a plate 36 50 having trunnion-like members 37 extending through the tube slots 33 and provided with threads at their ends for engagement with the threads of the nut 30. It will now be seen that when the nut is turned, the plate 36 will be caused to travel toward or from the plate, depending upon the direction of rotation of the nut 30. Said plate 36 constitutes a carrier to which are secured two flexible ribbons 38. These ribbons pass 60 through slots in the plate 34 and extend downwardly towards the end of the pedestal. On each of the ribbons is slidably mounted a plurality of prisms in the form of wedge-like members 39, the small ends 65 of these wedges facing each other. To the

lower end of the ribbons is fixably secured a block 40 to prevent the wedges from sliding off the ribbons. The plate 34 serves as an abutment against which the upper wedge members will abut.

Assuming now that it is desired to secure the lamp stand to a round or irregular-shaped object, as indicated by the letter R in Fig. 7, the ribbons are extended through the bottom of the pedestal for a sufficient distance by shifting the sleeve 22 along the pedestal, this shifting being attainable by releasing the locking levers 24 as already explained. Upon turning of the nut 30 in such direction that the threaded carrier plate 36 will be moved away from the abutment plate 34 secured to the sleeve 22, the wedges 39 will first contact on their outer adjacent edges 41 and will tend to fulcrum on such edges, with the result that the ribbons passing through the wedges will assume a curved form, as clearly shown in Fig. 7, thereby securely gripping the object R therebetween. The degree of curvature imparted to the ribbon will obviously depend upon the angle between the sides of the wedges, the greater the angle the greater the curvature that may be given ribbons.

By reason of the fact that the ribbons tend to assume an arcuate form when the wedges are drawn together, a flat object is not gripped as firmly as a round or irregular-shaped object. To overcome this difficulty, the base members 14 and 15 may be employed in conjunction with the flexible members. As indicated in Fig. 5, the base members 14 and 15 may be turned in such a manner that they constitute jaws between which an object may be clamped. As previously stated, the members 14 and 15 are provided with pockets 20 and into these pockets the ends of the flexible members are inserted. Upon turning the nut 30 to draw the wedges together, a clamping action will be obtained on said members 14 and 15, as will now be readily understood, it being remembered that the tendency is for the terminal ends of the flexible members to approach each other when the wedges are drawn together.

It will be seen that the underlying principle of the improved clamping means resides in the fact that there is combined in the flexible member a plurality of elements of such shape that when drawn together in abutting relation the flexible element will be caused to assume a curved condition, the preferred form of said element being wedges. However, it is possible to use elements which are not wedge-shaped, as for example, round members or rods, the ribbon passing through said rods at one side of the center thereof, as illustrated in Fig. 7 wherein the round rods are indicated by numeral 42. As the rods are drawn together they will first contact at

points 43 at one side of the ribbon, and the fulcrum will then shift toward the ribbon as same begins to take on a curvature.

While I have described a construction with considerable particularity as to detail, it is to be understood that no limitations are intended except as may be called for in the appended claims. Thus, while I have illustrated the pedestal as being a rectangular tube, the same might very well be a tube of different cross-section. Other constructional details may also be varied without departing from the spirit of the invention.

What I claim is:

1. The combination in a clamping device, of a tube, a flexible member disposed lengthwise in said tube, a movable carrier within said tube to which one end of said member is attached, a plurality of fulcrum elements 20 slidably mounted on said member, a stop at the free end of said member to hold said elements in place on the same, means on said tube for moving said carrier, an abutment within said tube fixedly supported with respect to said means whereby said carrier may be moved with respect to said abutment, the said fulcrum elements being disposed on said flexible member below said abutment and the said member passing through said 30 abutment, the stop-carrying end of said flexible member extending beyond the adjacent end of said tube, said fulcrum elements, when said carrier is moved away from said abutment, adapted to impart a 35 curved form to that portion of the flexible member extending beyond the tube.

2. The combination specified in claim 1, and means associated with said tube forming a jaw member between which and said 40 flexible member an object may be clamped at the extended end of said member.

3. The combination in a clamping device, of a tube, a flexible member disposed lengthwise in said tube, a movable carrier within 45 said tube to which one end of said member is attached, a plurality of fulcrum elements slidably mounted on said member, a stop at the free end of said member to hold said elements in place on the same, means on said tube for moving said carrier, an abutment within said tube fixedly supported with respect to said means whereby said carrier may be moved with respect to said abutment, the said fulcrum elements being disposed on said flexible member below said 55 abutment and the said member passing through said abutment, the stop-carrying end of said flexible member extending beyond the adjacent end of said tube, said fulcrum elements, when said carrier is moved away from said abutment, adapted to impart a 60 curved form to that portion of the flexible member extending beyond the tube,

and a second flexible member and fulcrum 65 elements similarly disposed within said tube

in opposed relation to the other flexible member, whereby the two said members at their extended ends cooperate to form means for anchoring the device to an object.

4. The combination specified in claim 3, 70 the said fulcrum elements having their fulcrum points disposed between said tube and adjacent flexible member, whereby said flexible members may be curved toward each other to constitute a gripping claw at their 75 external ends.

5. The combination specified in claim 3, and a pair of jaws hinged to said tube, said jaws adapted to receive the extended ends of 80 said flexible members, the latter adapted to close said jaws about an object.

6. The combination specified in claim 3, a pair of jaws disposed at that end of the tube through which the flexible members extend, and means adapted to releasably hold 85 said jaws in laterally extended position whereby to constitute said jaws base members for supporting said tube in upright position, said jaws when released adapted to be swung into such position that each may receive one end of the adjacent flexible members, the latter adapted to close said jaws about an object.

7. In combination, a tube, a sleeve longitudinally adjustable on said tube, an internally threaded nut carried by said sleeve, an abutment within said tube having its opposite ends extending through longitudinally extending slots in said tube and anchored to said sleeve, a plate arranged within said tube and threadedly engaged by said nut whereby to be shifted thereby, a pair of flexible members secured at one end of said plate and extending through openings in the abutment toward the bottom of the tube, a 95 plurality of fulcrum elements slidably received on each of said flexible members between said abutment and the free ends of said flexible members, said elements having cooperating fulcrum points at one side of the flexible members, whereby as said elements are drawn toward each other a curved condition will be imparted to the flexible members.

8. In combination, a pedestal, members hinged to one end of the pedestal and together constituting in one position a base for supporting the pedestal in upright position and in another position constituting a pair of jaws between which an object may be gripped, and means extending through said pedestal adapted to close said jaws about the object.

9. In combination, a tube, a turnable ring mounted on said tube at one end thereof, a 125 pair of base members hinged to said ring, a laterally extending flange extending around the said end of the tube and having cutouts at opposite sides thereof, said hinged members adapted to be locked in laterally 130

extending position by said flange and when the ring is turned to a given position adapted to be swung on their hinges toward each other, and means adapted to close said members about an object.

10. A portable electric light stand comprising in combination, a tube having two longitudinally extending slots and spaced openings in mutually opposed relation; a sleeve adjustably mounted on said tube, means carried by said sleeve for cooperating with said openings to lock the sleeve in position, a pair of transversely extending members within the tube having extensions projecting through said slots, one of said members being anchored to the sleeve and the other relatively movable, a nut carried by said sleeve for moving the said other member, a pair of flexible ribbons anchored to 20 said movable member and extending through the other member, fulcrum blocks slidably carried by said ribbons below said anchored member, said ribbons adapted to be extended beyond the end of the tube by means of 25 said sleeve, a light-supporting fixture turnably mounted on said tube at the bottom thereof, a pair of hinged base members turnably secured to the tube at the lower end of same, said base members adapted to be 30 swung toward each other to constitute clamping means, and said ribbons adapted

to exert clamping action of said clamping means.

11. In a gripping device, the combination of a flexible member, a plurality of fulcrum elements slidably received on said member, said elements having fulcrum points at one side of said member, whereby as said elements are forced toward each other a bending of said member will be effected.

12. In a gripping device, the combination of a flexible member, and a plurality of wedge members slidably mounted on said member.

13. In a gripping device, the combination of a flexible ribbon, and a plurality of wedge members slidably mounted on said ribbon.

14. In a gripping device the combination of a pair of flexible members, a plurality of slidable fulcrum elements on said members, said elements adapted to initially fulcrum on each other at one side of said flexible members, an abutment through which said members pass at one of their ends, and means for moving said members with respect to said abutment, said elements when drawn toward each other imparting a curved form to said flexible members.

In testimony whereof I affix my signature.

STEFAN WIMMER.
